IMPROVEMENT IN CARDING ENGINES.

THOMAS McGUIRK AND ORIN COLE, OF MILLVILLE, MASSACHUSETTS.

Letters Patent No. 59,919, dated November 20, 1866.

SPECIFICATION.

TO ALL WHOM IT MAY CONCERN:

Be it known that we, THOMAS McGUIRK and ORIN COLE, of Millville, in the county of Worcester, and State of Massachusetts, have invented certain new and useful improvements in Carding Engines, and that the following is a full, clear, and exact description of the same, reference being had to the accompanying drawing, in which—

Figure 1 represents a side view of some of the principal parts of two carding engines with our improvements applied thereto; and

Figure 2 represents a plan of the same.

Carding engines, for carding wool for spinning, are generally used in sets of three, which are commonly called the first breaker, the second breaker, and the finisher. The first of these operates directly upon picked wool, the second operates upon the long rolls produced by the first, and the third upon the long rolls produced by the second. The wool is delivered by the third in a series of narrow fillets which are condensed into rovings, and the delivery is effected by means of doffing cylinders having narrow rings of card-teeth, or ring doffers, as they are frequently called. In order to save the labor and trouble of applying a series of the long rolls produced by one carding engine to the next in the set, an automatic feed apparatus has been devised to take the long roll produced by the former, and apply it crosswise in alternately opposite directions, and in continuous succession, to the feed apron of the latter. When such feeding apparatus is employed for the finisher, the outermost fillet delivered at each side thereof by the ring doffers has been found to be of such variable or small size, that the roving condensed from it is unfit for spinning with the others; consequently the outside rovings have been thrown aside as waste, and have been taken to the picker by hand, to be repicked and mixed in with new wool. The object of our invention is to save the labor, trouble, and expense of removing these waste rovings, and carrying them to and fro by hand; and it consists of the combination of the doffer that takes the outermost fillet from the finisher, and some one of the carding cylinders of the set of carding engines (say of the first breaker or of the second breaker) with conveying mechanism, which we call a creeper, and which takes the waste roving or fillet, and delivers it continuously to the carding cylinder, so that it is mixed up with the new wool as fast as produced, thus requiring neither trouble nor hand labor to dispose of it.

The mode in which we prefer to carry our invention into practical effect will be understood by reference to the accompanying drawings, in which A represents the main carding cylinder of a finisher, and A' the main carding cylinder of a second breaker working in connection with the finisher. Each of these carding engines is supposed to be fitted with the usual complement of feed rollers, licker-in, workers, strippers, fancy cylinder, doffer or doffers, and other customary appurtenances, the finisher having two ring doffers, B B', as is customary, and being provided with condensers, which may consist of sets of rubbing rollers C C', condensing tubes, or other suitable apparatus. The two carding engines are supposed to be connected by the automatic feeding apparatus, which, being well known to builders of carding engines, has not been represented in the drawings, and need not be described; but which receives the continuous roll delivered by the second breaker, and applies it to the feed apron of the finisher in the usual manner.

In the example represented in the drawing, the carding cylinder to which the waste is delivered is the main cylinder of the second breaker, and in order to carry away the outside rovings or fillets delivered by the ring doffers of the finisher, a conveying apparatus is used for the outer roving or fillet at each side of the finisher. Each conveying apparatus is composed, in the example represented in the drawings, of two creepers, consisting of endless belts and their appurtenances, one of these belts, D, extending horizontally along the floor, beneath the carding engines, to the vicinity of the main cylinder, A', to which the roving is to be delivered, while the other, D', extends from the delivery end of the first upwards, in an inclined direction, towards the main cylinder A'. These endless belts are supported upon suitable pulleys, a a a a, and are caused to move at about the same speed as that at which the rovings are delivered from the finisher, by means of suitable shafts, belts, and belt pulleys, the last belt being applied to a belt pulley connected with one of the carding engines, so as to move in conformity therewith. The roving or fillet delivered by the outer ring of one of the doffers, B', is taken to the end of this conveying mechanism, and is applied to it by means of a loose pressing roller, e, which rolls by friction upon the surface of the horizontal belt. The horizontal belt carries the roving to the inclined belt D', which, in turn, carries it to the main cylinder, A', of the second breaker; so that when the roving or felt is

once applied thereto, it is continuously taken up by this carding cylinder and mixed in with the new wool delivered by the licker-in. At the junction of the two belts we find it expedient to place a second pressing roller e' , to keep the roving in its place. The journals of both of the pressing rollers are arranged to work in the slots of standards, so that the rollers can accommodate their positions to variations in the roving.

The conveying apparatus at the other side of the finisher is constructed in the same manner, and receives, conveys, and delivers the outer roving delivered by the outermost ring (of the doffer) at that side of the finisher; and, as it is customary to place the same number of rings upon each doffer, the conveying apparatus at one side of the finisher in such case acts upon the roving delivered by one doffing cylinder, and the conveying apparatus at the other side acts upon that delivered by the other doffing cylinder.

The apparatus thus described effects the delivery of the waste rovings or fillets to the main carding cylinder of the second breaker, but by extending the conveying mechanism it might be arranged to deliver the waste to the main carding cylinder of the first breaker. Or, in place of delivering the waste directly to the main carding cylinder, the conveying mechanism may be modified to deliver it to one of the other carding cylinders of either machine, or to drop it upon the feed apron; in either of which cases it is passed to the main carding cylinder and recarded with the other wool. Moreover, instead of using the outer doffer rings of the ring doffers to take the strands from the finisher, special narrow doffers may be used for the purpose.

Having thus described the best mode in which we have thus far embodied our improvements, what we claim as our invention, and desire to secure by Letters Patent, is—

The combination of the doffer of the finishing carding engine with one of the carding cylinders and a conveying mechanism, the whole operating substantially as set forth.

In testimony whereof we have hereunto set our hands this first day of June, A. D. 1866.

THOMAS McGUIRK,
ORIN COLE.
